DOOR CHIME

Norman William Stevenson, Macclesfield, England, assignor to V. & E. Friedland Limited, Macclesfield, England, a British company

Filed Mar. 12, 1962, Ser. No. 69,209

Claims priority, application Great Britain Sept. 13, 1961

Term of patent 14 years

(Cl. D72—1)

FIG. 1.

FIG. 2.

FIG. 4

FIGURE 1 is a perspective view of a door chime showing my new design;

FIGURE 2 is a rear perspective view thereof;

FIGURE 3 is an enlarged fragmentary sectional view taken on line 3—3 of FIG. 1; and

FIG. 4 is a front elevational view of the door chime illustrated in FIGS. 1—3.

I claim:

The ornamental design for a door chime, as shown.
